UNITED STATES PATENT OFFICE

HURNDON F. SHUFORD, OF LA GRANGE, GEORGIA

LOOP SELVAGE DEVICE

Application filed October 13, 1930. Serial No. 488,448.

This invention relates to an attachment for looms, the primary object of the invention being to provide an attachment of this character to facilitate the construction of special 5 loop selvages on heavy fabrics.

An important object of the invention is to provide an attachment of this character which will gradually feed the wire, used in forming the loop selvage on heavy cloth, thereby 10 changing the point of contact between the lay of the loom and the wire, to insure against the wire breaking, due to wear caused by the lay moving thereover.

A further object of the invention is to provide 15 an attachment of this character which may be readily and easily installed on a loom, without the necessity of making alterations in a loom construction, to mount the device.

With the foregoing and other objects in view, which will appear as the description proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

Referring to the drawings:

Figure 1 is a longitudinal sectional view 30 through a loom equipped with an attachment constructed in accordance with the invention.

Figure 2 is a fragmental elevational view of the attachment.

Figure 3 is a fragmental plan view illustrating 35 the pawl and ratchet employed in transmitting movement of a power shaft to the reel of the device.

Figure 4 is a sectional view through the 40 hollow pawl supporting arm.

Figure 5 is a fragmental sectional view through a modified form of the invention.

Figure 6 is a rear elevational view, illustrating 45 the modified form of the invention.

Figure 7 is a sectional view through the wire reel.

Figure 8 is a sectional view taken at right angles to Figure 7.

Figure 9 is a side elevational view of the 50 modified form of the invention, and illustrat-

ing the brake construction that prevents overrunning of the reel.

Referring to the drawings in detail, the reference character 5 designates the end supports of the frame of the loom to which the 55 front bar 6 and rear bar 7 are connected. The reference character 8 designates the warp threads of the cloth being woven, and as shown these threads pass over the roll 9, through the heddles, and through the reeds 60 of the lay, in the usual and well known manner.

The reference character 10 designates the wire used in the construction of the loop selvage of heavy cloth material, the wire being 65 wound on the drum 11, which is mounted in the frame 12, which in turn is secured to the bar 7, as clearly shown by Figure 2 of the drawings. It will, of course, be understood that the wire 10 passes through the eye of the outer heddle and is shed thereby to form the selvage loops. The frame 12 is formed with grooves to receive the shaft 13 of the weighted roller, which contacts with the wire 70 to permit the wire to be properly fed from the drum 11. At one end of the shaft on which the drum 11 is mounted, is a gear 15, which is engaged by the worm 16 mounted on the upper end of the vertical shaft 17, so that rotary movement of the shaft 17 will be 75 imparted to the drum, to unwind the wire 10, mounted thereon.

At the lower end of the shaft 17 is a ratchet wheel 18 which is engaged by the sliding pawl 19 that moves in the hollow shaft 20, the pawl being held to its extended position by means of the spring 21. As clearly shown by the drawings, the lower end of the shaft 17 is mounted in the bearing 22.

The hollow shaft 20 extends laterally from the upper end of the bell crank lever 23. The lower end of the bell crank lever is indicated by the reference character 24, and as shown has pivotal connection with the rod 25 that carries an eccentric 26 at its lower end, the eccentric being mounted on the power shaft 27, so that rotary movement of the power shaft will act to reciprocate the rod 25, to operate the bell crank lever connected therewith.

In the form of the invention as shown by sheet 2 of the drawings, the reference character 28 designates the reel within which the wire, used in forming the loop selvage, is mounted, the wire passing through an opening in the reel 28, as clearly shown by Fig. 7 of the drawings. Connected with the reel 28 is a coiled spring 29 that has connection with the arm 30, that is secured to the frame of the loom, the spring acting to yieldingly hold the reel in its normal position. The reel 28 is mounted on the shaft 31 which in turn is mounted in bearings formed at the upper ends of the arms 32, one end of the shaft 31 extending beyond the reel 28, where it is supplied with a ratchet wheel 33.

Cooperating with the ratchet wheel, is a pawl 34 carried at one end of the arm 35, which is also mounted on the shaft 31, the arm 31 extending to a position beyond the periphery of the ratchet wheel 33.

Connected with the arm 35 is a link 36 which in turn is connected with one end of the arm 37, the opposite end of the arm being connected with the rod 38, which carries an eccentric 39 at its lower end, the eccentric being mounted on the power shaft 40.

A brake band 41 operates in connection with the ratchet wheel 33 and acts to restrict movement of the ratchet wheel and shaft operated thereby. A coiled spring 42 is used in connection with the wire over which the loops of the selvage are formed, to hold the wire taut at all times.

From the foregoing it will be obvious that due to the construction shown and described, the wire is constantly being moved forwardly at a rate of speed slower than the speed of travel of the cloth being woven, to the end that the lay, which in the present showing is indicated by the reference character 43, contacts with the wire at various points throughout the length thereof, to the end that wear of the wire caused by the lay contacting therewith, is reduced to the minimum.

I claim:

In a loom, the combination of warp-carrying means including a heddle, with a wire threaded through the eye of the heddle and carried by the warp-carrying means to extend along an edge of the warp to form filling loops in the selvage, and means operated to feed the wire through the heddle eye at a slower rate of advance than the travel of the warp to shift the bending point of the wire in the heddle eye.

In testimony that I claim the foregoing as my own, I have hereto affixed my signature.

HURNDON F. SHUFORD.
